UNITED STATES PATENT OFFICE.

ARAUNA M. VAIL, OF PHILADELPHIA, PENNSYLVANIA.

DESIGN FOR A PERFUMERY-BOTTLE.

SPECIFICATION forming part of Design No. 24,750, dated October 15, 1895.

Application filed October 30, 1894. Serial No. 527,492. Term of patent 3½ years.

To all whom it may concern:

Be it known that I, ARAUNA M. VAIL, a citizen of the United States, residing in the city and county of Philadelphia, State of Pennsylvania, have invented and produced a new and original Design for a Perfumery-Bottle, of which the following is a specification, reference being had to the accompanying drawings, forming part thereof.

10 The leading feature of my design for a perfumery-bottle is a cap for the mouth of the same of the form of a bust of a human being with a collar on the neck of the same.

15 In the drawings, in which Figure 1 represents a perspective view of a perfumery-bottle

embodying my design and Fig. 2 represents a vertical section thereof, A designates a perfumery-bottle, on the mouth of which is a cap B, which is of the form of the bust of a human being, the same being hollow, covering the mouth of the bottle and having on the neck thereof the collar C. 20

What I claim is—

The design for a perfumery bottle, substantially as shown and described.

ARAUNA M. VAIL.
